(57) CLAIM

The ornamental design for a pet food bowl and tray, as shown and described.

DESCRIPTION

FIG. 1 is a rear, top perspective view of a pet food bowl and tray, showing my new design;

FIG. 2 is a front, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded perspective view of the pet food bowl and tray, shown disassembled for completeness of illustration.

The broken lines in the figures illustrate portions of the pet food bowl and tray that form no part of the claimed design.
